UNITED STATES PATENT OFFICE

EMANUEL AUFIERO, OF BROOKLYN, NEW YORK.

HAND-OPERATED SIGNAL.

1,207,834.

Specification of Letters Patent. Patented Dec. 12, 1916.

Original application filed May 31, 1912, Serial No. 700,675. Divided and this application filed February 20, 1913. Serial No. 749,662.

To all whom it may concern:

Be it known that I, EMANUEL AUFIERO, a citizen of the United States of America, residing at Brooklyn, in the county of Kings 5 and State of New York, have invented new and useful Improvements in Hand-Operated Signals, of which the following is a specification.

This invention relates to a device adapted 10 to emit sound for alarm, signal or other purpose, and more particularly to a hand-operated diaphragm horn, especially for use on automobiles, in which the sound is generated by rapid vibration of the diaphragm.

15 In general, the object is the construction of an improved device of this class, easy to operate, and always reliable and effective.

This is a division of my prior application filed May 31, 1912, Serial No. 700,675.

20 In the accompanying drawing, illustrating one embodiment of the invention, Figure 1 is a sectional view, with parts in elevation; and Fig. 2 is a detail view illustrating a preferred form of cam teeth for the rotatable 25 diaphragm-actuator.

30 3 is a suitable casing having an opening at one side or end closed by a diaphragm 5 and a casing member 6, the diaphragm being clamped between said member 6 and a frame 30 or clamping member 4, to which latter the casing 3 is attached by any suitable means. The diaphragm 5, which may be such as commonly employed in automobile horns, has at its center a beveled wear-piece 11 35 adapted for engagement by the teeth of a toothed rotor or diaphragm-actuator 10. A shaft 9 is journaled to rotate in supports 7 and 8, which may be bracket arms projecting from the part 4.

40 A ratchet wheel 19 is secured rigidly to the shaft 9, and a pawl 20 is adapted to engage said ratchet. Said pawl is carried by a sleeve 21 loosely fitted on shaft 9. Said sleeve 21 is rotated in response to pull on 45 the Bowden wire 13, which latter is connected to one end of a flexible steel band 14, the other end of which coils about and fastens to the sleeve 21. A coiled flat spring 22 has one end fastened to sleeve 21 and its 50 other end secured to support 7. The Bowden wire has a flexible tubing 13 and extends to a manually-actuated member, here shown as a reciprocating lever 17 carried by a bracket 16. It will thus be understood

that actuation of the lever 17, imparting a 55 pull to the Bowden wire 13, will operate through the steel band 14 and pawl-and-ratchet mechanism to rotate the shaft 9 in one direction, and that, as soon as the Bowden wire is released, spring 22 will return 60 the Bowden wire sleeve 21, and pawl 20 to their starting position.

By increasing the weight of the diaphragm-actuator 10 with a lead member 18 or other suitable means, the momentum 65 given to said diaphragm-actuator, or diaphragm-actuating means, by the initial pull of the Bowden wire, will continue the rotation of said diaphragm-actuator 10, the spring 22 in the meantime returning sleeve 70 21, pawl 20, and Bowden wire 13 to normal starting position, ready for a new pull from the Bowden wire. The spirally arranged spring 22 is contracted and expanded within its own plane, and has the advantage of 75 its susceptibility of being wound up to a very substantial extent by a plurality of revolutions imparted to the sleeve 21, so as to produce a plurality of revolutions of the shaft and diaphragm-actuator 10 for each 80 pull of the Bowden wire.

In practice, it is found that the weighted diaphragm-actuator 10 acts as an efficient regulator of speed; it stores up some of the power of the sudden impulses imparted to 85 it by the manual actuating means, and gives out such power for a period continuing beyond the period of positive actuation of the manual means, and between succeeding intermittent actuations of said manual means, 90 thus tending to effect uniformity of speed.

The teeth of the diaphragm-actuator 10 vibrating the diaphragm may be rounded at the tips, as shown in Fig. 2. The actuator 10 operates in one direction of rotation only, 95 and the teeth move with the abrupt end forward, in the direction of the arrow 24. With this arrangement it will be found that the time of contact between the diaphragm wear-piece and the actuator teeth is much 100 lessened and the impulses imparted to the diaphragm will be more sudden, producing a more efficient warning note.

What is claimed is:

1. In a device of the character described, 105 a diaphragm, energy transmitting means, and energy receiving, storing and imparting means adapted to receive energy from the

- transmitting means, said second means being always free immediately to transmit said energy to the diaphragm.
2. In an alarm or signaling apparatus, a diaphragm, a wear-piece carried by said diaphragm, a rotor adapted to actuate said wear-piece to vibrate the diaphragm, said rotor constituting a heavy fly-wheel having a relatively large mass, and manually actuated means for intermittently energizing said fly-wheel and vibrating the diaphragm for a period of time extending beyond the period during which energy is applied to said fly-wheel.
3. In an alarm horn or signalling apparatus, a diaphragm, a rotatable member adapted to vibrate said diaphragm, and actuating means intermittently in operative engagement with said diaphragm vibrating member, said member constituting an energy reservoir having capacity to produce continuous vibration of the diaphragm during intermittent movement of said actuating means of sufficient frequency to generate a continuous note.
4. In a device of the character described, a diaphragm, and means for vibrating the diaphragm, comprising energy transmitting means, and energy receiving and imparting means of large mass receiving the energy from the transmitting means, and adapted to resist the influence of irregularly applied energy and to move with gradually increasing and decreasing velocity.
5. In a signaling device, in combination, a casing, an elastic diaphragm, a wear-piece at its center, a shaft approximately parallel to the diaphragm, a weighted rotary member on said shaft at approximately right angles to the shaft and diaphragm and provided with projections at its periphery adapted to engage said wear-piece and to vibrate the diaphragm, a sleeve loosely mounted on said shaft, one-direction connecting means between said sleeve and said shaft, a cord attached to said sleeve and wound thereon adapted to directly apply the operator power to rotate said sleeve, shaft and weighted rotary member when the sleeve is operatively connected to the shaft, and a spring element having one end attached to the sleeve and its other end to the casing for moving the sleeve idly in the opposite direction while the weighted rotary member continues its motion in the first-named direction by virtue of its inertia.
6. In a signaling device, in combination, an elastic diaphragm, a shaft approximately parallel thereto, a weighted rotary member driven thereby and having projections at its periphery adapted to engage the diaphragm at its center and to vibrate the same, reciprocating mechanism actuated by the operator and mounted on said shaft, connecting means between said reciprocating mech-
- anism and the shaft for directly applying the operator power to impart motion in one direction only to the weighted rotary member through said shaft, and means for returning said reciprocating mechanism idly to normal position while the weighted member is free to rotate in the first named direction.
7. In a signaling device, in combination, an elastic diaphragm, a wear-piece at its center, a shaft, a fly-wheel element mounted thereon and provided with projections adapted to engage said wear-piece and to vibrate said diaphragm, a reciprocating mechanism, means connecting said reciprocating mechanism and said shaft for rotating said shaft and said fly-wheel element in one direction only, and means for idly moving the reciprocating mechanism in the opposite direction, while said fly-wheel element is free to continue to revolve in the first-named direction by virtue of its inertia.
8. In a signaling device, in combination, a casing, an elastic diaphragm closing an open side of said casing, a wear-piece at the center of said diaphragm, a shaft, a fly-wheel element within the casing and mounted on said shaft and provided with projections adapted to engage said wear-piece and to vibrate said diaphragm, a manually operable reciprocating mechanism, means within the casing connecting said reciprocating mechanism and said shaft for rotating said shaft and said fly-wheel element in one direction only and means for idly moving the reciprocating mechanism in the opposite direction while said fly-wheel element is free to continue to revolve in the first-named direction by virtue of its inertia.
9. In a signaling device the combination of a diaphragm and a diaphragm-displacing element, a shaft therefor, a ratchet secured to said shaft, a sleeve loosely mounted on said shaft, a pawl carried by said sleeve and adapted to engage said ratchet, a cable fastened to said sleeve and wound thereon being adapted to rotate said sleeve and shaft and diaphragm-displacing element in one direction when pulled by the operator, and a tension member adapted to idly rotate said sleeve in the opposite direction.
10. In a device adapted to emit sound for alarm, signal or other purpose, the combination of a casing, a diaphragm secured to said casing, a rotatable shaft within the casing, a weighted diaphragm-actuator on said shaft within the casing, and adapted to act as a fly-wheel, manual driving means operable from the exterior of the casing through an opening in the casing wall to the interior thereof to intermittently apply driving power, and interposed clutch means within the casing transmitting one-direction rotation from the manual means to the actuator and leaving the actuator free to con-

tinue its rotation by inertia at times when driving power is not being transmitted thereto.

11. In a device adapted to emit sound for alarm, signal or other purpose, the combination of a casing, a diaphragm secured to said casing, a rotatable shaft within the casing, a weighted diaphragm-actuator on said shaft within the casing in rotatable engagement 10 with said diaphragm to vibrate the same and adapted to act as a fly-wheel, power means manually-operable in one direction and extending from the exterior of the casing through an opening in the casing wall to the 15 interior thereof, means for automatically returning said power means in the reverse direction, and interposed clutch means within the casing transmitting one-direction rotation from the power means to the diaphragm-actuator and leaving said actuator free to continue its rotation by inertia at times when driving power is not being transmitted thereto.

12. In a sound-emitting apparatus, the 25 combination of a diaphragm carrying a projection, a shaft, a toothed rotor carried by

said shaft and engaging said projection for vibrating said diaphragm, and reciprocatory actuating-means comprising a sleeve loosely journaled on said shaft, pawl-and-ratchet 20 members carried by said shaft and sleeve respectively, a flexible pulling-member secured to said sleeve and passing around the same, and a spring secured at its inner end to said sleeve and disposed spirally around the same 35 and secured fixedly at its outer end.

13. In a sound-emitting apparatus, the combination of a diaphragm carrying a projection, a shaft and a toothed rotor carried thereby to engage said projection to vibrate 40 said diaphragm, and reciprocatory means for actuating said rotor comprising a spirally-arranged spring surrounding said shaft and having its inner end connected thereto, and a flexible pulling-member connected to said shaft and passing frictionally 45 around the same.

EMANUEL AUFIERO.
